ADDISON C. FLETCHER, OF NEW YORK, N. Y.

Letters Patent No. 64,090, dated April 23, 1867; antedated April 18, 1867.

AIR-HEATING APPARATUS FOR STEAM-BOILER FURNACES, &c.

The Schedule referred to in these Letters Patent and making part of the same.

TO ALL WHOM IT MAY CONCERN:

Be it known that I, ADDISON C. FLETCHER, of the city, county, and State of New York, have invented a new and useful improvement in Apparatus for Heating Air, to be supplied to furnaces, or for other purposes, also applicable to the condensation of the exhaust steam from an engine; and I do hereby declare that the following is a full, clear, and exact description of the same, reference being had to the accompanying drawings, forming part of this specification, in which—

Figure 1 is a vertical sectional view, illustrating the application of my invention to the heating of air for the supply of the furnace of a steam boiler by the waste heat in the smoke-stack or chimney.

Figure 2 is a horizontal section of the smoke-stack and air-heating apparatus, in the plane indicated by the line xx of fig. 1.

Figure 3 is a vertical section, illustrating the application of my invention to the condensation of the exhaust steam from an engine.

Similar letters of reference indicate corresponding parts in the several figures.

This invention consists in a novel arrangement of an air-heating passage within the smoke pipe, chimney, or upright flue of a steam-boiler or other furnace, or within the exhaust-steam pipe of an engine, in connection with an air-jacket surrounding such pipe, chimney, or flue, whereby air drawn or forced through the said passage and jacket is effectually heated by the waste heat of the escaping gaseous or fuliginous products of combustion or exhaust steam, for the promotion of combustion in the boiler or other furnace, and whereby also, in the case of the application of the invention to an exhaust-steam pipe, the condensation of steam for the production of a partial vacuum, and the saving of the water of condensation at a high temperature, for return to the boiler, or for any other use, is effected.

To enable others skilled in the art to apply my invention to use, I will proceed to describe it, with reference to the drawings.

A (fig. 1) is a steam boiler, and B is its furnace. C (figs. 1 and 2) is the smoke pipe or chimney. D is the air-jacket, surrounding the smoke pipe or chimney concentrically, made of sheet metal or other material, and closed at the bottom, but having openings $a a$, at equal intervals apart, all around it near the top, for the entrance of air. E is the air-passage, which constitutes the principal feature of the invention, formed of sheet metal, and extending diametrically or otherwise transversely across the smoke pipe or chimney, the whole or nearly the whole length thereof, and communicating along its whole or nearly its whole length with the interior of the air-jacket D, on opposite sides of the smoke pipe or chimney. The lower part of the jacket is connected on opposite sides, and opposite to the openings of the passage E, by two branch pipes $g g$, with a pipe, G, leading to the inlet pipe or eye of a rotary fan blower, F, the outlet or discharge pipe of which is supposed to lead to the boiler furnace.

The operation of the example of my apparatus represented in figs. 1 and 2 is as follows: The fire having been well started, and the blower being in action, the blower tends to produce a partial vacuum in the air-jacket D and air-passage E, and cold air, from outside of the jacket D rushes in to fill this vacuum through the openings $a a$. This air, circulating through the jacket and passage E, as shown in black arrows in fig. 1, on its way to the blower is heated by contact with and radiation from the heated exterior of the smoke pipe or chimney, and also by contact with and radiation from the interior surface of the passage E. This passage being surrounded by the hot gaseous and fuliginous products of combustion, ascending through the smoke pipe or chimney, constitutes, in proportion to its area, the most effective heating surface. The air having been thus heated, is drawn into the blower, and driven therefrom into the furnace, either above and below, or both above and below the grate.

In the application of the invention to the exhaust pipe of a steam engine, the exhaust pipe I is arranged as shown in fig. 3, on the top of a hot well, J, and open at the bottom thereto; and the jacket D, transverse air-passage E, and air pipes $g g$, are arranged in the same manner, in relation with the said pipe J, as they are in relation with the smoke pipe or chimney C, and the air is caused to circulate through the said jacket, passage, and air pipes, in the same manner as through those applied to the smoke pipe or chimney, by means of a blower connected with the pipe G; and the air, thus heated in the jacket and air-passage, is driven by the

blower to the furnace, or to wherever else it is to be utilized. The exhaust steam, entering the upper part of the hot well, circulating upward within the exhaust pipe, is in part condensed by the heat abstracted by the air; and the water of condensation, trickling down the interior surfaces of the jacket and exterior of the air-passage E, runs into the hot well, whence it is drawn off, at a nearly boiling temperature, to be supplied to the boiler, or for any other purpose.

Instead of a single air-passage, E, extending transversely through the smoke pipe or chimney, or through the exhaust pipe, a series of air-passages, arranged one above another, may be employed as an equivalent, such passages extending in the same manner transversely through the pipe or chimney, and communicating with the jacket in the same manner, on opposite sides thereof. And instead of the said single air-passage, there may be two or more air-passages, crossing each other at right angles, each communicating with the jacket on opposite sides of the pipe or chimney. The air, instead of being drawn by the blower through the said air-passage, may be driven or forced through them by a blower, the outlet of which communicates with the inlet openings of the jacket. The relative positions of the inlet and outlet openings of the jacket D may be reversed, the inlet being in that case at the bottom, and the outlet at the top.

What I claim as my invention, and desire to secure by Letters Patent, is—

The air-passage or passages E, extending transversely across and through the smoke pipe, chimney flue, or exhaust pipe, for the whole or nearly the whole length of, and in combination with, the jacket D, surrounding the said pipe, chimney, or flue, substantially as and for the purpose herein specified.

ADDISON C. FLETCHER.
